CLAIM

The ornamental design for a granular material self-unloading wagon or the like, as shown and described.

DESCRIPTION

FIG. 1 is an elevational view of one side of a granular material self-unloading wagon showing my new design; FIG. 2 is a top plan view thereof as seen along the line 2—2 in FIG. 1;

FIG. 3 is a front elevational view thereof, as taken along the line 3—3 in FIG. 2;

FIG. 4 is an elevational view of the other side thereof as taken along line 4—4 in FIG. 3;

FIG. 5 is a rear elevational view thereof as taken along the line 5—5 in FIG. 4; and

FIG. 6 is a view similar to FIG. 1, and showing the boom element thereof in its transport position.
